UNITED STATES PATENT OFFICE

GEORGE F. ABERLE, OF PHILADELPHIA, PENNSYLVANIA, ASSIGNOR TO H. C. ABERLE CO., OF PHILADELPHIA, PENNSYLVANIA, A CORPORATION OF PENNSYLVANIA

DESIGN FOR A STOCKING

Application filed June 8, 1931. Serial No. 40,131. Term of patent 3½ years.

To all whom it may concern:

Be it known that I, GEORGE F. ABERLE, a citizen of the United States, residing in Philadelphia, Pennsylvania, have invented a new, original, and ornamental Design for a Stocking, of which the following is a specification, reference being had to the accompanying drawings, forming part thereof, in which:—

Fig. 2 is a fragmentary view showing the design in enlarged detail which encircles the entire cuff of the stocking.

I claim:—

The ornamental design for a stocking, substantially as shown and described.

GEORGE F. ABERLE.
